UNITED STATES PATENT OFFICE.

JOHN J. GOTTSCHALK, OF TAUNTON, MASSACHUSETTS, AND BURTON W. PHELPS, OF PROVIDENCE, RHODE ISLAND.

SANITARY PIPE-STEM.

No. 904,323.

Specification of Letters Patent.

Patented Nov. 17, 1908.

Application filed April 22, 1908. Serial No. 428,487.

To all whom it may concern:

Be it known that we, JOHN J. GOTTSCHALK, a resident of Taunton, in the county of Bristol and State of Massachusetts, and BURTON W. PHELPS, a resident of Providence, in the county of Providence and State of Rhode Island, both citizens of the United States, have invented a new and Improved Sanitary Pipe-Stem, of which the following is a full, 10 clear, and exact description.

The purpose of the invention is to provide a stem adaptable to any pipe and so constructed as to form within the stem a reservoir for the collection of saliva and the reception of foreign substances, preventing such factors collecting in the bowl of the pipe or its stem except in said reservoir.

It is a further purpose of the invention to so construct the stem that it will be sanitary 20 and so that it may be adapted to any character of bowl.

The invention consists in the novel construction and combination of the several parts, as will be more fully hereinafter 25 described and claimed.

Reference is to be had to the accompanying drawings forming a part of this specification in which similar characters of reference indicate corresponding parts in all 30 the views.

Figure 1 is a sectional side elevation of a smoking pipe having the improved stem applied; Fig. 2 is a longitudinal section through the improved sanitary stem disconnected from the bowl of the pipe; Fig. 3 is a side elevation of the inner tube of the stem, located mainly in the reservoir thereof; and Fig. 4 is a longitudinal section through a slightly modified form of the improved 40 stem.

The improved stem is adapted to be introduced in an air-tight manner into the stem extension A from the bowl B of a tobacco pipe of any desired shape and character. 45 The bore 10 of the said stem extension A is tapered at its outlet end, and at said end receives the outer end portion of the improved sanitary and detachable stem C, having integral therewith or detachable therefrom a 50 suitable mouthpiece 11. In the drawings, the mouthpiece 11 is shown integral with the auxiliary stem. This auxiliary stem C is enlarged diametrically at its outer end, or the end that is adapted to enter and is fitted 55 to the main stem A connected directly with

the bowl B, and is correspondingly tapered to the interior taper at the outlet end of said main stem, as is shown in Fig. 1, the tapered portion of the auxiliary stem being designated as 12.

The outer tapered end of the auxiliary or improved stem is enlarged and its bore is increased diametrically over that of the bore 13 in the mouthpiece section 11, to provide a chamber or reservoir 14 for the reception 60 and retention of saliva and particles drawn from the bowl B of the pipe when the pipe is in use.

The reservoir 14 may be of any desired dimensions and receives an inner or distributing tube D, that extends beyond its outer 65 end and practically to its inner or mouthpiece end.

The distributing tube D is provided with an outer plug terminal section 15 that closes 70 the outer end of the reservoir when the tube is properly inserted therein, as is shown in Fig. 1. The outer end of the said plug section 15 is of less diameter than that of the bore of the main stem A into which it extends, as is also shown in Fig. 1, and that portion of the plug section 15 of the distributing tube D that extends beyond the outer 75 end of the auxiliary stem C is provided with an annular groove 16, constituting an air 80 vent that facilitates the draft and the leading of the saliva and particles drawn from the bowl B to the reservoir 14. The inner end of the distributing tube D is a blind end, being suitably closed, as is shown at 85 17 in Figs. 2, 3 and 4, and adjacent to this blind end 17 of said distributing tube one or more, usually two, apertures 18 are produced, permitting the smoke drawn into said tube to pass to the mouthpiece section of the auxiliary stem C, while the saliva and accompanying 90 particles find lodgment in said reservoir 14.

The auxiliary stem C is held, preferably by frictional engagement, in the main stem 100 A, but the engagement may be otherwise effected, and the distributing tube D may be held in the auxiliary stem C by frictional contact, as is shown in Fig. 2, or a screw connection may be effected, as illustrated at 105 19 in Fig. 4.

The auxiliary stem C may be readily disengaged from the main stem A, and should any matter lodge in the main stem it can be 110 readily removed therefrom, and upon re-

moving the distributing tube D from the reservoir 14 the latter may be readily and quickly cleaned.

Ample space is provided between the blind 5 end of the distributing tube D and the wall of the reservoir 14, to permit the ready passage of smoke to the mouthpiece section of the auxiliary stem.

Having thus described our invention, we 10 claim as new and desire to secure by Letters Patent:

The combination with the bowl of a pipe and the stem extension, of a shove bit mouth piece having in its inner end a longitudinal 15 recess, forming a reservoir and communicat-

ing with the bore of the mouth piece, and a distributing tube extending into the recess, the inner end of the tube being closed and flanged laterally, said end being of smaller diameter than the recess, the tube being provided with side openings, and having an annular groove at its outer end portion. 20

In testimony whereof we have signed our names to this specification in the presence of two subscribing witnesses.

JOHN J. GOTTSCHALK.
BURTON W. PHELPS.
